UNITED STATES PATENT OFFICE.

WILLIS E. GROH, OF CORUNNA, INDIANA.

SAND PUMP.

Application filed April 3, 1926, Serial No. 99,551. Renewed July 12, 1928.

This invention relates to improvements in sand pumps of that type employed for the recovery of sand and gravel from river beds, and the objects thereof are to provide a 5 revolving head in connection with the suction pipe constructed so that the submerged bed of gravel, sand and the like will be loosened and a proper quantity of water admitted with the loosened material into the 10 mouth of the suction pipe; to provide a cutting head in connection with the suction pipe constructed in a manner as to prevent choking of material in the head and mouth of the suction pipe and thereby obviate in- 15 terruption in the operation of the apparatus; and to provide in connection with the suction pipe and cutting head a shield applied in such manner as will prevent the cutter head from becoming overwhelmed by cav- 20 ing material and the operation thereof thus interrupted.

These objects are accomplished by the construction illustrated in the accompanying drawings, in which:—

25 Fig. 1 is a side elevation of the suction pipe of a sand pump, and showing the present invention in connection therewith;

Fig. 2 is a vertical section of a cutting head in connection with the mouth of the 30 suction pipe and including a portion of the shield;

Fig. 3 is a top plan view of the cutting head and shield, and including a portion of the suction pipe; and

35 Fig. 4 is a bottom plan view projected from Fig. 2.

The characters appearing in the description refer to parts shown in the drawings and designated thereon by corresponding 40 characters.

In Fig. 1 is shown a fragment of float or barge 1 which constitutes the support for the pumping apparatus of which the suction pipe 2 is a part. The suction pipe has a 45 downturned mouth section 3 at its outer end and a flexible connection 4 at its inner end, the latter admitting vertical adjustment of the suction pipe. The flexible connection is coupled by means of a pipe 5 with a pump, 50 which, being of usual construction is not here shown, and the suction pipe is suspended from a boom 6 and tackle 7 in the customary manner so that the suction pipe may be raised and lowered as required.

55 On the lower end of the mouth section 3 of the suction pipe is mounted in axial aline-

ment therewith a cutter head 8 consisting of a cylinder 9 having an annular series of teeth 10 made in its lower end, and having at its top a gear 11 forming a closed head 60 therefor, said gear being rotatably mounted on the pipe 3. An annular collar 12 is fixed on the pipe 3 below the hub 13 of the gear 11, and a bracket 14 is fixed on said pipe above said hub so that vertical movement of the gear on said pipe is prevented. The cutter head has fixed therein at a point approximately midway between the lower end of the pipe 3 and the lower end of the cylinder 9 a series of cross-bars 15 disposed 65 transversely in the cylinder to form a grating therein for the purpose hereinafter set forth.

A countershaft 16 is mounted in an arm 17 that extends from the bracket 14, and 70 also in a supporting arm 18 that is mounted on the pipe 3 near its upper end, and upon the lower end of said countershaft is fixed a pinion 19 that meshes with the gear 11 so that as the countershaft 16 revolves the cutter-head is actuated accordingly. Upon the upper end of the countershaft 16 is fixed a bevel gear 20 that meshes with a companion bevel gear 21, which latter bevel gear is 75 mounted upon and has splined relation with a propeller shaft 22 by which the countershaft is actuated. The propeller shaft is mounted in brackets 23 on the suction pipe and is jointed, there being a universal joint 24 provided to admit of a corresponding 80 bending action of the propeller shaft when the suction pipe is adjusted. The rear end of the section 25 of the propeller shaft has connection with a gearing 26 by means of 85 which the propeller shaft is actuated.

A shield consisting of a curved plate 27 is mounted upon arms 28 that project from the bracket 14 and also upon a spider 29 that is fixed upon the pipe 3 at a point thereon above said bracket. The lower end of the 90 shield 27 overhangs the gear 11 and the upper portion of the cylinder 9 so that the front of the cutter head is sheltered thereby.

In operating the invention suction is established in the suction pipe, and the gearing 26 is driven in the usual manner from a suitable source of power (not shown) such as is ordinarily provided for actuating similar apparatus. The suction pipe is then lowered into the water and the cutter head, 100 while being revolved comes into contact with the submerged earthen material while water

is being drawn up through the cylinder and into the suction pipe. As the earthen matter is loosened by the action of the cutter head and rush of water, it becomes broken up, 5 and the particles of sand and gravel are drawn up through the suction pipe with the flow of water and are from thence disposed of in the usual manner through the pumping mechanism. Stones and other substances 10 too large to pass between the cross bars 15 are prevented by the grating from rising and choking the suction pipe, and when their accumulation in the lower end of the cylinder becomes objectionable, their removal is 15 effected by elevating the suction pipe.

What I claim is:

1. In apparatus of the class described including a vertically adjustable suction pipe and means for supporting same in adjusted 20 positions, a cylindrical cutter head rotatably mounted on the suction pipe in axial alignment therewith, a portion thereof extending beyond the mouth of said pipe, the upper end of said head being closed, and its lower 25 end being toothed; a grating fixed in the head disposed between the toothed end of the head and the mouth of said pipe; a driving mechanism including means for actuating same, having geared relation with said 30 cutter head; and a shield in supported relation with said suction pipe and overhanging the upper portion of said cutter head.
2. In apparatus of the class described including a support, an angular suction pipe 35 in vertically adjustable relation with said support; a rotatable cutter head mounted on said suction pipe and surrounding the mouth thereof; a countershaft in supported relation with said suction pipe and having gear- 40 ed relation with said cutter head; an actuating mechanism on said support; a propeller shaft having an universal joint therein, one portion of said propeller shaft having supported relation with said suction pipe and 45 being longitudinally adjustable relative

thereto, the other portion of said propeller shaft having driven relation with said actuating mechanism; and a pair of bevel gears meshed with each other one of which is fixed on said countershaft, and the other 50 of said bevel gears being mounted upon and having splined relation with said propeller shaft.

3. In apparatus of the class described including a supporting means, a suction means in vertically adjustable connection with said supporting means; a cutter head rotatably mounted upon said suction means at the mouth thereof; a mechanism, including actuating means therefor, having geared relation with said cutter head; and a semi-circular shield in supported relation with said suction means and overhanging the upper front portion of said cutter head. 55

4. In apparatus of the class described including a supporting means, an angular suction pipe in vertically adjustable supported connection with said means; a cylindrical cutter head rotatably mounted on said suction pipe and surrounding the mouth thereof; a shield consisting of a curved plate mounted upon said suction pipe and overhanging the upper portion of said cutter head and extending throughout its length 70 in parallel relation with the cylindrical wall 75 of said cutter head; and actuating means for said cutter head.

5. In apparatus of the class described, an excavating means including a movable suction pipe and rotating cutter head encompassing the intake end of said pipe, and a semi-circular non-rotatable shield, the lower portion of which overhangs the front upper portion of said cutter head, the lower end and rear portions of said cutter head being 80 exposed. 85

In testimony whereof I affix my signature.

WILLIS E. GROH.
